UNITED STATES PATENT OFFICE.

GUILLAUME CLEMENT LAURENCY, OF MIDDLESEX, ENGLAND.

MEANS FOR THE PARALLELIZATION OF TEXTILE FIBERS IN MACHINES FOR PREPARING SAME FOR SPINNING.

Application filed November 28, 1925, Serial No. 72,045, and in Great Britain December 5, 1924.

The purpose of the present invention is to enable machines which prepare textile materials for spinning, such as carding engines, to straighten and parallelize the fibers or filaments of these materials, so that the said fibers or filaments may be placed lengthwise before passing on to the operations following that of carding.

Broadly stated, the invention consists in using in conjunction with cylinders provided with needle points or card clothing one or more cylinders having a covering of leather or other similar material, or provided with channels in the metal surface of the said cylinders, in combination with flexible blades pressed against a circumferential portion of said cylinders in order to obtain friction between the leather or channels and said blades, the said friction commencing at a point close to the said needles or card clothing in order to remove the fibers lodged between them, and the said fibers being forcibly straightened and rendered parallel by sliding between the said needles which advance more slowly than the leather covering or channels of the cylinders.

The invention further comprises novel details of construction, arrangement and combinations of parts all as hereinafter fully described and set forth in appended claims.

The accompanying drawings show examples of the application of this invention to existing machines.

Figures 1, 2, 3 and 4 are partial views showing the invention applied to a carding engine which delivers the fibers in the form of a continuous fleece over the whole width of the machine, which fleece may be rolled up in superposed layers or otherwise in the usual manner, or can also be condensed into a single ribbon, or divided into narrow ribbons which are condensed in the rubbers and which, in this case, form the slivers or preparation yarn for spinning machines.

Figs. 5 and 6, respectively, show the application of the invention to a carding engine having a jing doffer, and to one with double ring doffers, these two machines, as is known, supplying the fleece in the form of narrow ribbons, as above mentioned.

In these examples the cylinders A, B, C rotate at progressive circumferential speeds. The cylinders A and C are clothed with leather or other similar material, but not of a slippery nature, and the cylinder B is pro-

vided with fine needles inclined or hooked, like the teeth of card-clothing. The cylinder A is placed adjacent the doffer of the carding engine, partly represented at D in Figs. 1 and 2, at D¹ in Fig. 5, and at D¹ 60 and D² in Figs. 5 and 6.

A portion of the circumference of each of the cylinders A, B, C is surrounded by very flexible metal blades, which are pressed against the peripheries of the said cylinders 65 by spring members, and said spring-members, which secure the contact of the blades with the cylinders, are fastened to cross-bars G placed longitudinally beneath the said cylinders.

In the construction shown in Figs. 1, 2, 3 and 4, the blades a, which surround a portion of the cylinders A, B, C, are inclined to the axes of the cylinders at about 30°, and form segments of a helix which meet in 75 close points or meet closely at their edges, the friction of the cylinders constantly tending to press them together. In the construction illustrated in Figs. 5 and 6, the blades a' are placed at right angles, that is to say, 80 perpendicularly to the rotary motion of the cylinders, and they do not contact with each other. These blades give, owing to their resiliency, each time the machine delivers the fibers in the form of a continuous fleece 85 over the whole working width of the carding engine, in order to prevent the fibers from being held back at the junctions of the said blades; they may be at right angles, as shown in Fig. 5, when the fleece is divided into 90 ribbons before undergoing the operation of combing and drawing, because the said blades can be wider than the said ribbons without meeting one another.

This width of the blades depends further 95 on their flexibility and on the rigidity of the cylinder on which they work; they can besides be so much wider as the cylinder is more rigid and a single plate pressed on all the length of this cylinder by the series of 100 springs e can even in this case assure the drawing along of the fibers.

The fibers, which the main cylinder of the carding machine has deposited between the needles of the doffer D, are withdrawn from 105 the latter by the cylinder A when they reach the point m; and are then conveyed by the leather surface of this cylinder A and pressed against this surface, they slide over the blades at a speed equal to that of 110

the periphery of the said cylinder. As the circumferential speed of the cylinder A is greater than that of the doffer D, the fibers drawn by said cylinder are compelled to slide between the said needles of the doffer, whereby the rear portion of the said fibers is straightened and arranged parallel with the movement of the cylinders by this movement, since the needles of the doffer advance 5 more slowly than the leather covering or channels of the cylinder. The forward portion of the fibers which first reaches the point *n*, is then straightened and made parallel, in its turn, by the cylinder B, which 10 has a circumferential speed greater than that of the cylinder A; the needles of said cylinder B slide between the fibers as long as the latter are held by the blades on the cylinder A, but when the fibers are 15 completely free at the point *n* from said cylinder A, they advance with the needles of cylinder B to the point *m* of the cylinder C, and the latter draws them also at an accelerated speed which causes them to slide 20 again between the needles of cylinder B, but in a direction contrary to the former as they are again drawn by their forward portion.

The principle of combing and drawing of the fibers in both directions in carding machines, which was devised by myself in 1900, has never yet been utilized for the following reasons:—As will be seen from the specification of English Letters Patent No. 30 18,781, A. D. 1900, which was granted to me at that period, I employed cylinders having an elastic covering, the friction of which in a cavity formed in a rigid metal block effected the drawing and conveyance of the fibers, but it was impossible to practically obtain a regular pressure for this friction over the whole length of the cavity with 35 cylinders which could only be supported at their ends. It is true that the elastic covering of the cylinders permitted of obtaining friction over the whole surface, but the pressure of this friction varied at all points in the length of the cylinder and moreover, this elasticity prevented the combing and 40 drawing by hindering the entrance and conveyance of the fibers into the cavity.

An elastic covering is compressed before entering the cavity of the metal block, its friction producing a swelling of the flexible material at the entrance side for the fibers, and the greater the pressure of the cylinder, the more this swelling extends beyond the rigid or hard edge of the metal block. The seeds, lumps and other impurities which 45 travel with the fibers are not conveyed with them into the cavity, but remain at the entrance thereof on the rigid edge of the metal block causing accumulation of fibers to which they close the passage and which become hardened by the friction of the casing 50

while producing in the latter grooves, the depth of which increases at each revolution of the cylinder. Notwithstanding the elasticity of the material, these grooves continue to exist after the removal of the callosities 55 which have occasioned them, and they form breakages of contact between the cylinder and the cavity of the metal block. Now this contact is indispensable over the whole length of the cylinder in order to cause the 60 fibers to slide between the needles and consequently attain the object of the invention. The provision of channels in the said elastic covering has not removed these inconveniences but on the contrary has furthered the 65 formation of the grooves while increasing the degree of swelling of the fibers above mentioned.

The substitution for the rigid metal block of the flexible blades above described, such 70 as those shown in Fig. 5, combined with a leather covering for the cylinders, without elastic foundation has imparted to the cylinders a sufficient rigidity while transferring the elasticity to the equivalent of the metal 75 block, and the defects referred to were disposed of, but in spite of the greatest care débris of the fibers, seeds and other impurities were arrested at the junction of the blades, hindering the regular forward movement 80 of the fleece. The helical arrangement of the blades shown in Fig. 2 was necessary to remove this fresh inconvenience, and these blades form a partial casing 85 flexible at all points of its surface and its contact is assured with an equal pressure 90 over its whole length. The blades are separately moved away from the cylinder to allow the accumulation of fibers and foreign 95 bodies presenting themselves, and the fibers 100 pass freely over the junction of the blades which they traverse obliquely.

It has, therefore, been impossible to put 105 into practice my said prior invention because of the defects above briefly pointed out; therefore the combing and drawing and the parallelization of the fibers in the carding engine were not realized thereby.

The length of the blades which work with the cylinder B must be greater than that of the longest fibers, so that the latter may never be engaged at the same time by both cylinders A and C, whereas they can very well be engaged at the same time by the doffer D, cylinder A and cylinder B, since 110 their ends can slide between the needles of the doffer D as well as between those of cylinders A and B; and for this reason a greater diameter is given to the said cylinder B.

The clothing for the cylinders A and C can be provided with straight or helical channels, and in certain cases, said clothing can be replaced by grooves cut in the metal 115 of the cylinder. The acceleration of speed 120

of the cylinders depends on the amount of combing and drawing to which the kind of fiber is to be subjected, and this combing and drawing operation can of course be repeated by increasing the number of cylinders.

It is to be remarked that Fig. 2 shows in plan a portion of the doffer D with the cylinders and flexible blades seen in section in Fig. 1. Fig. 5 shows the arrangement of the blades placed at right angles, and employed for the combing and drawing of ribbons obtained with the ring-doffer D¹, and Fig. 6 shows on a reduced scale an application of the invention to a carding engine having double ring doffers like that shown in Fig. 5. In this last case the invention must obviously be applied to each of the two doffers, as indicated in said Fig. 6.

The fibers deposited by the main cylinder T of the carding engine between the needles mounted on the rings of the doffers D¹ and D², are removed by the cylinder A and transmitted to the successive cylinders B and C in the same manner as described in the first construction and the ribbons, which are of the same width as the doffer rings, are then condensed in the rubbers F and H and wound in the usual manner.

It will be seen that in this application of the invention the combing and drawing operations are performed, after the division of the fleece, and the parallelism of the fibers obtained thereby is not deranged.

The drawing operation which is effected at the same time as the combing, allows the ribbons to be considerably elongated, and consequently slivers may be produced as fine as desired with rings of ordinary width on the doffers. The result is that the application of the invention to machines with a ring doffer or two ring doffers permits the use of apparatus known as "tape condensers" and the like to be dispensed with, the sole purpose of which is to enable slivers to be obtained of a finer character than with the ring doffers. The slivers with parallel fibers are moreover much more easily elongated in the spinning machines.

For the first passage of the fibers through the carding machine, the cylinder B of Fig. 1 can be provided with very inclined conical needles and the speed of the cylinder C considerably increased in relation to that of the cylinder B. In these conditions the fibers are more quickly withdrawn from the nee-

dles of cylinder B, leaving the waste and impurities between the latter, and a circular brush shown at R in Fig. 1 removes them and throws them into a receptacle in the known manner. This brush is not required for the following passages since all the fibers are removed from the cylinder B by the cylinder C.

What I claim as my invention and desire to secure by Letters Patent of the United States is:—

1. In a machine for preparing textile materials for spinning, the combination, with a cylinder provided with card clothing and with rollers having their surfaces adapted to retain and convey the fibers by friction, of a set of flexible blades arranged helically over a portion of the circumferences of the said cylinder and rollers; the blades of each helix thus formed being pressed one against another by the rotation of corresponding cylinder or roller and forming a flexible casing at all points of its surface, the fibers drawn along by the friction being adapted to traverse said blades obliquely.

2. In a machine for preparing textile materials for spinning, the combination with cylinders and rollers, and flexible casings partly surrounding the same, of springs adapted to force said casings against the cylinders and rollers while allowing the casings to move therefrom in order to afford passage to foreign substances of greater volume than the fibers, and rigid supports for said springs.

3. In a machine for preparing textile materials for spinning, the combination with a doffer having card clothing of a cylinder, rotating at a greater circumferential speed than said doffer, such cylinder having a rigid fluted surface which cannot be deformed, and a casing constituted by a plurality of elastic blades adapted to be pressed against a circumferential part of said cylinder to obtain a uniform and limited friction between the rigid surface of said cylinder and the polished surface of said blades, such friction removing the fibers lodged between the teeth of said doffer, and the said fibers being forcibly straightened and rendered parallel by sliding between said teeth, due to the greater surface speed of said cylinder.

In witness whereof I have signed this specification.

GUILLAUME CLEMENT LAURENCY.
